CLAIM

I claim the ornamental design for a travel pillow, as shown and described.

DESCRIPTION

FIG. 1. Is a front elevational view of a travel pillow showing my new design.

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
